UNITED STATES PATENT OFFICE.

BIRGER LJUNGSTRÖM, OF STOCKHOLM, SWEDEN, ASSIGNOR TO AKTIE-BOLAGET SEPARATOR, OF STOCKHOLM, SWEDEN.

LINER FOR CENTRIFUGAL LIQUID-SEPARATORS.

No. 822,964.

Specification of Letters Patent.

Patented June 12, 1906.

Application filed May 3, 1905. Serial No. 258,566.

To all whom it may concern:

Be it known that I, BIRGER LJUNGSTRÖM, a subject of the King of Sweden and Norway, residing at Stockholm, Sweden, have invented certain new and useful Improvements in Liners for Centrifugal Liquid-Separators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 It is well known that the skimming capacity of a centrifugal bowl is considerably increased by dividing the bulk of the milk, by insertion of conical plates or the like, in a radial direction into thin laminae or strata and 20 that the separating process takes place the easier the thinner the laminae or strata are. There is, however, a certain limit, which thereby may not be exceeded. The cream is 25 namely a slow-flowing liquid, and if the space between the plates exceeds a certain limit the cream passes only with difficulty and relatively slow between the plates, and the skimming capacity thus becomes decreased. For the purpose of increasing the 30 number of plates to be inserted in a bowl of fixed height the thickness of the plates has been reduced as much as possible; but also in this respect a certain limit must be fixed, depending on the stability to be given to such 35 plates for preventing them from being deformed by the action of the centrifugal force or in cleansing them.

The present invention has for object to increase the number of insertion-plates, and 40 thus the number of laminae or strata, without decreasing the solidity of the plates and without checking the cream separated in the spaces between the plates in its flowing inwardly toward the center of the bowl. For 45 this purpose the division-plates are made decreasing in thickness from their outer to their inner ends, and in this way the plates may be placed nearer each other without decreasing the spaces for the inwardly-flowing cream. 50 The spaces between the plates thus becomes smallest at the periphery of the bowl, where the outflowing liquid essentially consists of blue milk, which is quick-flowing, and greatest at the center of the bowl, thus leaving

sufficient room for the relatively slow flowing cream to find its way to the cream-outlet.

In the annexed drawings a centrifugal bowl is shown in Figure 1 in vertical section, provided with a liner insertion consisting of conical plates continually decreasing in thickness from their outer to their inner ends. Fig. 2 shows a detail.

a is the bowl, and *b* represents the plates, which in the usual manner are provided with angle-bent edges *c* and *d*. As shown, the spaces between the plates are continually increasing in height from the periphery to the center of the bowl, thus leaving the necessary space for the separated cream in proportion to its separation and forming a thicker 75 layer. It is hereby possible to increase the number of plates in a bowl of fixed height, and thus to increase proportionally the skimming capacity of the bowl without decreasing the stability of the plates. Preferably both the inner and the outer edges of the plates are thicker than the plate itself nearest to the said edges, as shown in Fig. 2, in order to increase the stability of the plates. This has no influence on the escape of the 80 cream and the skim-milk.

I do not limit my invention to liners consisting of conical plates, the same being applicable to all division contrivances by which the bulk of the rotating liquid is divided in 85 the radial direction into thin laminae or strata.

What I claim is—

1. The combination of a centrifugal separator-bowl with division-plates intersecting both radial horizontal and radial vertical 90 planes of the bowl, said plates continually decreasing in thickness from the outer to the inner ends and having their outer edges bent outwardly and their inner edges bent inwardly, the inner edge being thicker than the 95 plate itself nearest said edge.

2. The combination of a centrifugal separator-bowl with division-plates intersecting both radial horizontal and radial vertical 100 planes of the bowl, said plates continually decreasing in thickness from the outer to the inner ends and having their outer edges bent outwardly and their inner edges bent inwardly, the outer edge being thicker than the plate itself nearest said edge. 105

3. The combination of a centrifugal separator-bowl with division-plates intersecting both radial horizontal and radial vertical

planes of the bowl, said plates continually decreasing in thickness from the outer to the inner ends and having their outer edges bent outwardly and their inner edges bent inwardly, both the inner and the outer edges being thicker than the plate itself nearest said edges.

In testimony that I claim the foregoing as my invention I have signed my name in presence of two subscribing witnesses.

BIRGER LJUNGSTRÖM.
